UNITED STATES PATENT OFFICE.

CARLETON ELLIS AND ALFRED A. WELLS, OF MONTCLAIR, NEW JERSEY, ASSIGNEES
TO ELLIS-FOSTER CO., A CORPORATION OF NEW JERSEY.

MAKING NITRO COMPOUNDS.

1,220,078.

Specification of Letters Patent. Patented Mar. 20, 1917.

No Drawing.

Application filed May 31, 1916. Serial No. 100,776.

To all whom it may concern:

Be it known that we, CARLETON ELLIS and ALFRED A. WELLS, citizens of the United States, and residents of Montclair, in the 5 county of Essex and State of New Jersey, have invented certain new and useful Improvements in Making Nitro Compounds, of which the following is a specification.

This invention relates to the preparation 10 of nitro aromatic bodies such as the nitro derivatives of benzol and the like and relates particularly to the production of nitro-phenols suitable for use in the manufacture of picric acid and sulfur black. The invention will be illustrated with respect to the 15 preparation of dinitrochlorbenzol and the corresponding dinitrophenol.

Picric acid is usually manufactured from carbolic acid, which may be obtained in a 20 state of comparative purity and the picric acid obtained thereby if carefully prepared is almost chemically pure. The specifications of the various governments for picric acid to be used as an explosive are very 25 rigid, calling for a product of the utmost purity.

Numerous attempts have been made to 30 prepare picric acid from sources other than carbolic acid but most of these do not give a product answering to the requirements of a high explosive. For example, the melting point may be too low or the ash content too high or the product discolors on heating or contains free acid and the like. By the 35 present process it is possible to obtain for example, dinitrophenol in such a state of purity that picric acid may be prepared therefrom by further nitration, which product possesses the properties required.

In carrying out the present process, illustratively, the prepared raw material is chlorbenzol and in preparing this product by the chlorination of benzol a certain amount of dichlorbenzol and other bodies are obtained 45 which are somewhat troublesome to completely eliminate from the chlorbenzol. The latter also may contain a trace of benzol, toluol, xylol, and the like, if not carefully prepared. These impurities appear at a 50 later stage to militate against the purity of the resulting product, and oftentimes are

found very troublesome to eliminate. One 55 phase of the present process is that impurities are satisfactorily eliminated and a product of high quality is obtained.

The present process also contemplates the preparation of nitrochlor compounds such 60 as mononitrochlor and dinitrochlorbenzol by the action of nitric acid liberated from sodium nitrate or equivalent nitrate by the action of a compatible acid such as sulfuric acid, in part at least in the presence of 65 chlorbenzol so that a condition of nascent 70 is secured and a part at least of the freshly liberated nitric acid is caused, or allowed, to react with the chlorbenzol under conditions to form the mono or dinitrochlorbenzol to especially good advantage and with suitable heating or cooling as the case may be to maintain a temperature such that the 75 liberation of nitric acid progresses smoothly and the nitration of the chlorbenzol progresses in a controllable manner thereby minimizing the formation of impurities, by-products such as tars and resins and diminishing the danger of explosions such as may occur when large quantities of mixed nitric 80 and sulfuric acid are allowed to react on such raw materials. Whether the satisfactory result obtained in the present invention is directly due to the condition of nascent 85 of the nitric acid or to its preparation, *in situ*, or whether the gradual formation of the nitric acid under preferred conditions of operation is conducive to a more controllable reaction within the limits desired, is difficult to state and it may be possible 90 that both of these factors are active in the satisfactory progress of the reaction.

The process also makes it possible to use sulfuric acid of a comparatively low grade such as 66° B. acid instead of 96% or fuming sulfuric acid which are more costly and also avoids the shipment of liquid nitric acid, as the nitrating material is employed 95 in the form of a dry salt.

In chlorinating benzol, as stated, it is not 100 always possible to secure the monochlorbenzol without the formation of other bodies which are undesirable, and moreover, in nitrating chlorbenzol to form dinitrochlorbenzol, more or less mononitrochlorbenzol 105

and the like may be formed, especially if great care is not taken in every stage of the operation. Hence the conversion of material prepared in this manner into dinitrophenol and subsequent transformation into picric acid yields a product which ordinarily has a low melting point or in other respects does not respond to the official tests. In the present process when directed to the production of dinitrophenol and picric acid, means are provided as stated, for eliminating at one or more stages of the operation all or substantially all of these impurities, enabling a product of excellent quality to be prepared.

15 The following serves as an illustrative method of procedure:—

20 About 2 parts by weight of sodium nitrate (crystals) and 6 parts of sulfuric acid of 66° Bé. are placed in a nitrating kettle equipped with a mechanical stirrer and with heating and cooling coils or jackets and are agitated until the sodium nitrate is practically all in solution. In some cases this mix may be separately prepared. 1 part or so of monochlorbenzol is then added slowly, while the mixture is cooled, the temperature not being allowed to rise above 100° C. After the chlorbenzol has all been added the 25 temperature is maintained at about 100° C. for several hours and it is then gradually raised until at the end of say about 15 hours nitration, the temperature has reached preferably about 125° C. Nitration is carried 30 on at this temperature until the nitration is complete which will require about 24 hours. During this operation the control of temperature may be best observed by watching the yellowish to reddish fumes given off from the nitrating mixture. If properly conducted, at no time should there be a copious evolution of nitric or other nitrogen oxid fumes as this means a loss of nitric acid. A vent pipe from the nitrating kettle may be 35 fitted with a sight glass to determine the depth of color of the fumes. If of a deep red color and copious in amount the reaction is progressing too violently for best results and economy of acid. When the 40 operation is complete the contents of the nitrating kettle are allowed to stand for a short while until they have separated in two molten or liquid layers. The top layer consists of the nitrated bodies while the lower 45 layer consists of a mixture of sodium sulfate, sulfuric acid and a small amount of nitric acid. The lower layer may be drawn off and is valuable in many technical operations for its acid content. The top layer is then 50 drawn off into another vessel where it is treated with water to remove free acid and the dinitrochlorbenzol thus obtained is suitably collected. Or the layer of nitrated bodies may be hydrolyzed with approxi- 55 mately a 10 per cent. solution of caustic

soda which removes the combined chlorin and produces the sodium salt of dinitrophenol. If this operation is carried on in too concentrated solutions the sodium phenate will crystallize out which is preferably to be avoided. The alkaline solution is boiled without pressure for about two hours which usually will suffice to completely convert the dinitrochlorbenzol into sodium dinitrophenate, without affecting mononitrochlorbenzol. Live steam is then turned 70 into the boiling mixture and the whole mass thoroughly steamed, as long as any oily bodies come over as may be shown by a condenser attached to the receptacle. When 75 oily particles cease to be discharged therefrom, this purification step is completed. The steaming operation serves to eliminate bodies such as mononitrochlorbenzol, etc.

80 Any tarry material or heavier oils which are not soluble in the alkaline solution, or removable by steaming, may be drawn off from the bottom of the hydrolyzing tank, thus further purifying the product. The remaining portion of the alkaline solution is drawn off to be acidified. The ordinary 85 procedure of acidification is to pour the diluted acid into the sodium salt, but a purer product is better obtained by reversing this operation and running the sodium salt into dilute acid. This product is readily filtered 90 on a cloth strainer and may be readily washed and dried by pressing in a bag press. For ordinary operations it is not essential to thoroughly dry the material before converting either into picric acid or into a dye- 95 stuff such as sulfur black although in the former case a saving in the amount of acid is secured. Thus according to the present invention, the preparation of dinitrophenol 100 of high purity may be accomplished by the use of sodium nitrate as a source of nitric acid in the nitration, by the control of temperature in such a manner as to make economic use of the materials used and to regulate the rate and degree of nitration and by the purification of sodium dinitrophenate 105 by distilling with steam and drawing off any alkali insoluble material while working in such dilutions as to keep the sodium salt 110 always in solution. With no purification steps other than those stated above it is possible to obtain dinitrophenol which is practically pure having substantially the correct melting point and possessing a good 115 color.

120 To recapitulate, this invention relates to the preparation of nitro bodies particularly nitrobenzols such as mononitrochlor and dinitrochlorbenzol and the corresponding phenols, namely: mononitrophenol and more particularly the higher nitrated phenols such as dinitro and trinitrophenol, which comprises treating, for example, chlorbenzol or similar chlorinated body 125

with sodium nitrate or equivalent nitrate and with a compatible acid capable of liberating nitric acid preferably sulfuric acid and heating to a temperature at which 5 nitration progresses preferably smoothly and regularly and without violent reaction and evolution of large quantities of oxids of nitrogen but proceeding instead in a controlled manner; whereby nitric acid is liberated 10 more or less regularly from the sodium nitrate and is in like manner united with the chlorbenzol forming the nitrochlorbenzols, preferably the dinitrochlor compound, with scarcely any loss of nitric acid; 15 thereby enabling approximately equivalent proportions of chlorbenzol and sodium nitrate to be employed in an advantageous and economical manner. And the invention further comprises the step of forming nitrophenols, preferably a compound such as dinitrophenol, in a substantially pure condition, as by incorporating crude dinitrochlorbenzol with aqueous alkali such as dilute caustic soda solution and in heating 20 without pressure or otherwise under conditions which substantially avoid the hydrolysis of mononitrochlorbenzol, to remove the chlorin from the dinitro compound and substitute the hydroxyl group thereby yielding 25 dinitrophenol in solution in the form of the sodium salt, and in separating any mononitrochlorbenzol from the sodium salt by steaming, settling and the like; whereupon the substantially pure sodium salt 30 may be acidified to liberate the dinitrophenol, which acidification step is preferably carried out by adding the sodium salt solution to an excess of acid rather than adding acid to the sodium salt solution, since by 35 the former procedure a product of lighter color is more likely to be obtained. The invention further contemplates the nitration 40 of the dinitrophenol under suitable nitrating conditions to form picric acid of satisfactory purity.

What we claim is:—

1. In the process of making nitro derivatives of benzol, the step which comprises heating a mixture comprising chlorbenzol, 50 sodium nitrate and sulfuric acid to a temperature at which nitration progresses regularly but at which no copious evolution of oxids of nitrogen fumes occurs.
2. In the process of making nitro derivatives of benzol, the step which comprises heating a mixture comprising chlorbenzol, alkali nitrate and sulfuric acid to a temperature at which nitration progresses regularly but at which no copious evolution of 55 red fumes occurs.
3. In the process of making nitro derivatives of benzol, the step which comprises heating a mixture of chlorbenzol, sodium nitrate and 66° B. sulfuric acid to a temperature at which nitration progresses 60 regularly but at which no copious evolution of red fumes occurs.
4. In the process of making derivatives of benzol, the step of nitrating chlorbenzol which comprises heating chlorbenzol, sodium nitrate and 66° B. sulfuric acid and nitric acid comprising nascent nitric acid to a temperature at which nitration progresses 65 regularly without evolution of large quantities of oxids of nitrogen.

larly but at which no copious evolution of red fumes occurs.

5. In the process of making derivatives of benzol, the step of nitrating chlorbenzol which comprises heating chlorbenzol with freshly-prepared nitric acid containing at least some portion thereof in a condition of 70 nascence.

6. In the process of making derivatives of benzol, the step of making dinitrochlorbenzol which comprises heating chlorbenzol, sodium nitrate and sulfuric acid to 75 a temperature in the neighborhood of but substantially not exceeding 130° C.

7. In the process of making dinitrophenol the step which comprises forming sodium dinitrophenate, in purifying the latter by 80 distilling with steam and drawing off any insoluble material from the dilute solution of the sodium dinitrophenate, and in acidifying the latter.

8. The process of purifying dinitrophenol 85 which comprises hydrolyzing crude dinitrochlorbenzol with a caustic soda solution of such dilution that the sodium dinitrophenate formed remains entirely in solution.

9. The process of making dinitrophenol 90 which comprises nitrating chlorbenzol with sodium nitrate and sulfuric acid in proportions to yield only a slight excess of nitric acid and in controlling the rate of formation of the nitric acid and in regulating the 95 temperature in such a manner that substantially no nitric acid is lost.

10. In the process of making derivatives of benzol, the step of making dinitrochlorbenzol which comprises heating chlorbenzol, 100 sodium nitrate and 66° B. sulfuric acid to a temperature at which nitration progresses smoothly without evolution of large quantities of oxids of nitrogen.

11. The process of purifying dinitrophenol 105 which comprises adding an alkaline solution thereof to a dilute solution of an acid.

12. The process of making dinitrophenol which comprises nitrating chlorbenzol with sodium nitrate and 66° B. sulfuric acid. 110

13. The process of nitrating chlorbenzol to form dinitrochlorbenzol which comprises treating chlorbenzol with a solution formed by mixing sulfuric acid and sodium nitrate.

14. The process of nitrating chlorbenzol 115 to form dinitrochlorbenzol which comprises treating chlorbenzol with a solution formed by mixing 66° sulfuric acid and sodium nitrate.

15. The process of nitrating chlorbenzol 120

to form dinitrochlorbenzol which comprises heating chlorbenzol with a solution formed by mixing sulfuric acid and sodium nitrate until the latter is practically all in solution.

5 16. The process of making dinitrochlorbenzol which comprises mixing about two parts of sodium nitrate (crystals) and six parts of sulfuric acid and in agitating until

the sodium nitrate is practically all in solution, and in reacting with this mixture on ¹⁶ approximately one part of monochlorbenzol while heating and agitating; whereby dinitrochlorbenzol is formed in substantial yield.

CARLETON ELLIS.
ALFRED A. WELLS.
